REFRIGERATING APPARATUS

Lawrence A. Philipp, Detroit, Mich., assignor, by
mesne assignments, to Nash-Kelvinator Cor-
poration, Detroit, Mich., a corporation of Mary-
land

Application April 20, 1933, Serial No. 666,944
Renewed January 24, 1935

11 Claims. (Cl. 62—95)

This invention relates to refrigerating apparatus and more particularly to the method and apparatus for controlling temperatures in such apparatus.

5 One of the objects of my invention is to provide a fundamentally new system and method of refrigeration wherein a simple compact unit is utilized for freezing ice cubes and the like and for cooling circulating air in a refrigerator cabinet in an improved manner without the collection of frost on its surfaces exposed to said circulating air at least part of the time.

Another object of my invention is to provide a refrigerating apparatus of the type which includes primary and secondary refrigerating systems for cooling a plurality of zones, and to provide an improved arrangement for maintaining a temperature differential between said systems.

Another object of my invention is to provide 20 a refrigerating apparatus of the type which includes a primary and secondary refrigerating system for cooling a plurality of zones, and to provide an improved method for maintaining a temperature differential between said systems.

25 Another object of my invention consists in an improved method of controlling temperatures in the primary and secondary systems of the aforesaid apparatus.

Another object of my invention is to utilize 30 the aforesaid secondary system for cooling circulating air in a food storage compartment of a refrigerator without collecting frost thereon at least part of the time due to the deposit of moisture from the circulating air, and to employ a 35 cooling element of the primary system for freezing substances, and also to enclose the primary cooling element against said circulating air, to thus avoid the necessity of rendering the primary refrigerating system inoperative for periodically defrosting any part of the apparatus.

Another object of my invention is to proportion 40 the effective area of the heat dissipating portion of the secondary condenser with respect to the heat absorbing area of the secondary evaporator to maintain a temperature differential between the heat absorbing medium of the condensing zone and the secondary evaporator.

Other objects and advantages will be apparent 45 from the following description, reference being had to the accompanying drawings.

In the drawings:

Fig. 1 is a vertical view in cross section of a refrigerating apparatus embodying features of my invention;

55 Fig. 2 is a view taken along the line 2—2 of

Fig. 1, with a portion of the enclosure for the cooling apparatus broken away;

Fig. 3 is a view of a modified form of refrigerating apparatus embodying features of my invention; and

Fig. 4 is a further modified form of refrigerating apparatus embodying features of my invention.

Referring to the drawings, the numeral 20 designates, in general, an insulated cabinet having 10 a food storage compartment 21, the inner walls of which are formed by a metallic liner 22. Preferably, the lining member 22 is provided with a coating of vitreous enamel, such as porcelain, to provide a neat appearance and surface which 15 may be easily cleaned.

Within the confines of the liner 22 there is disposed a refrigerant evaporating element 25 of a primary refrigerating system 27. The element 25 is of the plate type, which may be of any suitable construction, and is horizontally disposed in the cabinet slightly spaced from the top wall thereof. The element 25 is arranged for supporting ice making receptacles 26 on its upper surface immediately below the top wall of the cabinet 20.

In addition to the primary evaporating element 25, the primary refrigerating system 27 includes a compressor 30, motor 32, condenser 34, and a high side float mechanism 36. The compressor withdraws gaseous refrigerant from the element 25 through vapor return conduit 38, compresses the gaseous refrigerant and delivers it to the condenser wherein it is liquefied and from which it is delivered to the high side float 30 mechanism. Liquid refrigerant is delivered to the element 25 through a liquid supply conduit 35 40 under the control of float mechanism 36.

A secondary refrigerating system is provided 45 for cooling the circulating air in the compartment 21 and also, for supporting receptacles for freezing and storing frozen substances in close proximity to the primary evaporating element 25 where said substances will be frozen or retained in frozen condition by the refrigerating effect of the primary evaporating element 25.

The secondary refrigerating system 42 comprises, in general, a refrigerant evaporating element 45, the interior of which forms an evaporating region, and a refrigerant condensing element 46, the interior of which forms a condensing region. The elements 45 and 46 are connected together and are in open communication with each other by means of conduits 47. The secondary refrigerant evaporating element 45 is sub- 50 55

stantially of the same size as the primary refrigerant evaporating element 25 and is horizontally disposed within the cabinet directly below the element 25. The secondary evaporating element is arranged for supporting receptacles 49 on its upper surface and for cooling the circulating air in the compartment 21 by the circulating air contacting with the underside of said element. The secondary refrigerant condensing element 46 is, preferably, rectangular in shape and is disposed in contact with the primary evaporating element 25 for condensing evaporated refrigerant in the secondary system 42.

15 In order to maintain a temperature differential between the primary evaporating element 25 and the secondary evaporating element 45, I have constructed the secondary condensing element 46 so that the effective area for dissipating heat absorbed in the secondary system is considerably less than the heat absorbing area of the secondary evaporating element 45. As shown in Fig. 2, the secondary condensing element 46 is considerably smaller in size than the evaporating element 45. 20 By thus providing a relatively small condensing element 46, the surface thereof which contacts with the primary evaporating element will be such that only a portion of the evaporated refrigerant in the secondary system 42 will be condensed, and 25 a portion thereof is retained in vapor form in the condenser 46 where it applies a definite pressure upon the liquid refrigerant in the secondary evaporating element 45, to thus maintain a heat lag between the secondary evaporating element and 30 the primary evaporating element. Thus, by proportioning the effective heat dissipating area of the secondary condensing element and the heat absorbing area of the secondary evaporating element, a definite temperature differential may be 35 maintained between the primary and secondary refrigerating systems.

40 Referring now to Fig. 3, there is shown a modified form of condensing element for the secondary system 42. In this modified form of the invention, the secondary refrigerant condensing element 52 is provided for condensing evaporated refrigerant in the secondary system. As will be noted, the condensing element 52 is substantially the same size as the primary evaporating element 25. 45 In an arrangement of this type, I also proportion the effective area of the heat dissipating portion of the condensing element 52 with respect to the heat absorbing area of the secondary evaporating element. In this arrangement, however, 50 the effective area of the condenser 52 is limited by substantially entirely filling the secondary evaporating element and condensing element with liquid refrigerant so that the upper interior surface of the condensing element is partly in contact with some of the liquid refrigerant in the secondary system, and some of the upper interior surface of the condensing element is slightly spaced from the liquid refrigerant in the secondary system. Thus, the upper interior surface 55 of the condensing element 52 need not be all on the same plane but is slightly undulating so that portions thereof contact with the liquid refrigerant in the secondary system, while other portions thereof are slightly spaced from the liquid refrigerant in the secondary system. This limits the 60 effective area of the condensing element 52.

65 As shown in Fig. 4, another arrangement for maintaining a temperature differential between the primary refrigerant evaporating element and the secondary refrigerant evaporating element 53

in the aforesaid apparatus is to merely introduce a slight film of liquid refrigerant 54 into the refrigerant evaporating element so that the amount thereof is insufficient to at any time cool the surfaces of the secondary evaporating element to as 5 low a temperature as the quantity of liquid contained in the primary evaporating element cools the surfaces of the primary element.

Preferably, the temperature differential which is maintained between the primary evaporating 10 element 25 and the secondary evaporating element 45 is such that the circulating air in the compartment 21 is cooled to the desired temperatures without collecting frost on the surfaces of the evaporating element 45 at least part of the 15 time during its operation. This may be accomplished by operating the evaporating element 45 at temperatures which would allow the collection of a slight film of frost thereon during the on-phase of the refrigerating cycle of the primary 20 system 27, and allow the frost to be melted from the element 45 during the off-phase of the refrigerating cycle of the system 27. If desired, however, the secondary evaporating element may be operated at temperatures slightly above that 25 which would cause the collection of frost and ice thereon due to the deposit of moisture from the circulating air in the compartment 21.

In order to prevent the collection of frost and 30 ice on the primary evaporating element 25 and the upper surface of the secondary evaporating element 45, and to provide suitable freezing zones for the substances contained in trays 26 and 49, I have provided a metallic enclosure 60 and a front closure plate 62. The enclosure 60 is provided 35 with out-turned flanges 64 which are secured to the top wall of the cabinet 21 in any suitable manner, and in-turned flanges 66 which are secured to the top wall of the secondary evaporating element 45 in any suitable manner. The enclosure 60 forms a suitable enclosure for the sides and rear portion surrounding the primary evaporating element 25, the secondary condensing element and the top wall of the secondary evaporating element 45. The front closure plate 62 40 operates with the closure 60 for so enclosing the primary evaporating element, secondary condensing element and the top wall of the secondary evaporating element against the circulating air within the compartment 21. The front closure 62 45 is provided with openings 70 and 71 to permit the insertion and removal of the receptacles 26 and 49, respectively. The openings 70 and 71 are closed by doors 73 and 74, respectively.

In order to increase the heat transfer characteristics of the secondary evaporating element 45, I have provided a plurality of U-shaped heat absorbing fins 75. The fins are preferably equally spaced and arranged in parallel relation across the underside of the element 45. Immediately 60 below the secondary evaporating element 45, I have positioned a pair of baffles and drip conducting plates 78. The members 78 are arranged for directing the flow of air in the compartment 21, and also for receiving the drip water from 65 the secondary evaporating element 45 and conducting it to a drip receptacle 80 supported by shelf 82.

From the foregoing, it will be noted that I have provided an improved arrangement and 70 method for maintaining a temperature differential between a primary and secondary refrigerating system which is very simple to construct and is so arranged that it consists of no moving parts whatsoever or any parts in the secondary 75

system which would be likely to become faulty in operation to vary the temperature differential maintained between it and the primary system.

Preferably, the primary refrigerating system

5 27 is intermittently operated. In order to control the operation of said primary refrigerating system, I have provided an automatic thermostatically controlled switch 85, to which is connected a thermostatic fluid containing bulb 87, 10 which controls the operation of the switch 85 in the well known manner. The fluid containing thermostatic bulb 87 is placed in contact with a secondary evaporating element 45, to thus control the operation of the primary system in 15 response to changes in temperatures in the element 45. The switch 85 opens and closes the motor circuit to the power mains 90 in response to changes in temperatures in element 45.

Thus, it will be noted that predetermined temperatures may be maintained within the evaporating element 45, by controlling the operation of the primary refrigerating system in response to changes in temperatures in the secondary evaporating element 45. It will also be noted 25 that the relative temperatures existing in the secondary evaporating element 45 and the primary evaporating element 25 may be determined in various manners. In the embodiments of the invention disclosed, the heat lag between the 30 evaporating region and the condensing region is increased by reducing the amount of association between molecules of evaporated refrigerant and the condensing portion. This can be accomplished by limiting the effective area of the secondary condensing element relative to the effective area of the secondary evaporator, in which case an increased pressure is present in the secondary system which in effect reduces the vaporization in the secondary evaporator, or, this 35 reduction of the amount of association between molecules of evaporated refrigerant and the condensing portion can be accomplished by utilizing only a small amount of refrigerant in the secondary system. By these arrangements, ice cubes 40 and the like may be rapidly frozen by the refrigerating effect of the primary evaporating element, and the circulating air in the food storage compartment 21 may be cooled to its proper temperature for the preservation of foods stored in the compartment 21 without the collection of 45 frost and ice upon its exposed surfaces, or with the collection of a slight film of frost thereon during the on-phase of the refrigerating cycle of the primary system which is melted during the 50 off-phase of the refrigerating cycle of the primary refrigerating system. It will also be noted that by the arrangement of parts in the cabinet, the same element which cools the circulating air within the cabinet provides a support for receptacles containing substances to be frozen or to 55 be retained in a frozen condition by the refrigerating effect of a heat absorbing element which is provided for the rapid freezing of substances.

Although only a preferred form of the invention has been illustrated, and that form described in detail, it will be apparent to those skilled in the art that various modifications may be made therein without departing from the spirit of the invention or from the scope of the appended 60 claims.

70 What I claim as my invention is:

1. The process of refrigeration which consists in establishing refrigerant condensing and evaporating zones in open communication with each other, maintaining said zones substantially en-

tirely filled with volatile liquid refrigerant, evaporating the refrigerant in the evaporating zone, passing the evaporated refrigerant to the condensing zone and condensing evaporated refrigerant in the condensing zone.

5

2. Refrigerating apparatus comprising, in combination, a refrigerated shelf for freezing substances, a refrigerated shelf located directly below the first shelf, and means for operating the second shelf at least part of the time at temperatures above the freezing point of water, said second shelf having an air cooling portion and being provided with a surface for supporting frozen substances immediately below the first named shelf to thereby maintain said substances 15 in a frozen condition by the refrigerating effect of the first named shelf.

10

3. Refrigerating apparatus comprising, in combination, a cooling element for freezing substances, a second cooling element having a portion located directly below the first element, and means for operating the second element at least part of the time at temperatures above the freezing point of water, said second element having an air cooling portion and being provided with 20 a surface for supporting frozen substances immediately below the first named element to thereby maintain said substances in a frozen condition by the refrigerating effect of the first named element.

25

4. Refrigerating apparatus comprising, in combination, a cabinet having a food storage compartment, a cooling element disposed in said cabinet for freezing substances, a second cooling element disposed in said cabinet for cooling the 35 circulating air in said compartment, means for operating the first named cooling element at temperatures sufficiently low enough to cause rapid freezing of said substances, and means for operating said second named element at temperatures above that which would permit operation without collecting frost and ice thereon at least part of the time, and said second named cooling element being so positioned with respect to the first named cooling element that frozen 40 substances may be supported thereon to be retained in a frozen condition by the refrigerating effect of the first named cooling element.

45

5. Refrigerating apparatus comprising, in combination, a cabinet, a pair of vertically spaced 50 plate type evaporating elements disposed in said cabinet and being adapted to support ice making receptacles one above the other, means enclosing the upper element and the uppermost part of the lower element from the circulating air in the cabinet, and means for operating the lower element at a higher temperature than the upper element whereby the underside of the lower element may cool the circulating air in said cabinet without collecting frost thereon at least part of 55 the time, and the upper surface thereof may be used for supporting one of said ice making receptacles for freezing the contents thereof by the refrigerating effect of the upper element.

60

6. Refrigerating apparatus comprising, in combination, a cabinet, a pair of vertically spaced 65 refrigerant evaporating elements disposed in said cabinet and being adapted to support ice making receptacles one above the other, means enclosing the upper element and the uppermost part of 70 the lower element from the circulating air in the cabinet, means for operating the lower element at a higher temperature than the upper element whereby the underside of the lower element may cool the circulating air in said cabinet 75

without collecting frost thereon at least part of the time, and the surface thereabove providing a support for one of said ice making receptacles for freezing the contents thereof by the refrigerating effect of the upper element, and means responsive to changes in temperatures of the lower element for controlling the refrigerating effect of the upper element.

7. Refrigerating apparatus comprising, in combination, a cabinet having a food storage compartment, a primary refrigerating system including a refrigerant evaporating element disposed in said cabinet outside of direct contact with the circulating air in said compartment, a secondary refrigerating system including a refrigerant evaporating element disposed in the path of circulating air in the food compartment for cooling said air, said secondary system also including a condenser disposed in contact with the primary element, said secondary system being substantially entirely filled with liquid refrigerant to thereby produce a heat lag between the primary and secondary evaporating elements so that the secondary evaporating element operates at least part of the time without collecting frost thereon, and means for controlling the operating of the primary system in response to changes in temperatures in one of said systems.

8. Refrigerating apparatus comprising a cabinet having an insulated main food chamber, a refrigerating system comprising a cooling unit in said chamber, said unit including an enclosure having surfaces exposed for cooling circulating air in said chamber, and a refrigerated shelf positioned in said enclosure to divide the interior thereof into a relatively small freezing chamber and a relatively large storage chamber, and to refrigerate said enclosure, the exposed surfaces of said enclosure being so associated with said refrigerated shelf as to cool said main chamber to a refrigerating temperature, solely by the heat absorbing effect of said refrigerated shelf without the formation of frost thereon at least part of the time while the refrigerated shelf is maintained at a sharp freezing temperature.

9. Refrigerating apparatus comprising a cabinet having an insulated main food chamber, a refrigerating system comprising a cooling unit

in said chamber, said unit including an enclosure having surfaces exposed for cooling circulating air in said chamber, and a refrigerated shelf positioned in said enclosure to divide the interior thereof into two chambers, and means associated with said enclosure for controlling the temperature of said refrigerated shelf, said means being responsive to the changes in temperature of a surface of said enclosure to maintain a refrigerating temperature in said main food chamber solely by the heat absorbing effect of said refrigerated shelf without the collection of frost on the exterior surfaces of said enclosure at least part of the time while maintaining the refrigerated shelf at a sharp freezing temperature.

10. Refrigerating apparatus including a cooling unit adapted to be installed in an insulated food storage chamber comprising a metallic casing forming a secondary chamber, shelf means within said secondary chamber dividing the same into compartments of unequal height, means for refrigerating said shelf means, said secondary chamber having access means for said compartments and closure means for said access means, and means influenced by the temperature of said metallic casing for controlling the refrigerating effect of said shelf refrigerating means, said shelf refrigerating means being arranged to refrigerate at least the compartment above said shelf to temperatures below freezing and to absorb heat from said casing to refrigerate the food storage chamber without the formation of frost on said casing.

11. Refrigerating apparatus including a cooling unit adapted to be installed in an insulated food storage chamber comprising a metallic casing forming a secondary chamber, refrigerated shelf means within said casing for dividing said secondary chamber into a plurality of compartments and for refrigerating the same, and means including a thermo-bulb contacting a surface of said casing for controlling the refrigerating effect of said shelf means, said casing being arranged to refrigerate said insulated food storage chamber, without the collection of frost on said casing at least part of the time, solely by the refrigerating effect of said shelf means.

LAWRENCE A. PHILIPP.
